United States Patent Office

Des. 208,847
Patented Oct. 3, 1967

208,847

FAUCET

Herbert P. Senoff, East Brunswick, N.J., assignor to Allen-Stevens Drum Accessories Corp., South Plainfield, N.J., a corporation of New Jersey

Filed May 27, 1966, Ser. No. 2,448

Term of patent 14 years

(Cl. D91—3)

Fig. 1.

Fig. 2.

Fig. 3.

Fig. 4.

Fig. 5.

Fig. 6.

FIG. 1 is a perspective view of a faucet showing my new design;

FIG. 2 is a top view thereof;

FIG. 3 is a view of the threaded end of the faucet;

FIG. 4 is a side elevational view of the faucet;

FIG. 5 is a view of the other end of the faucet; and

FIG. 6 is a bottom view thereof.

The dominant features of my design reside in the portions shown in full lines.

I claim:

The ornamental design for a faucet, as shown and described.
